UNITED STATES PATENT OFFICE.

ROY H. McELROY, OF DAYTON, OHIO, ASSIGNOR TO THE INTERNATIONAL CLAY MACHINERY CO., OF DAYTON, OHIO.

COMPARTMENT-KILN.

1,254,421.

Specification of Letters Patent. Patented Jan. 22, 1918.

Application filed June 20, 1917. Serial No. 175,739.

To all whom it may concern:

Be it known that I, Roy H. McElroy, a citizen of the United States, residing at Dayton, in the county of Montgomery and State of Ohio, have invented certain new and useful Improvements in Compartment-Kilns; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in sectional kilns of the compartment type having bag walls on each side of the compartments. One object of the invention is to provide an improved communicating flue system whereby the burners in the bag walls are individually supplied with air, and another object of the invention is to provide an improved form of gas ducts whereby the gas is led to the burners from beneath the kiln. Other objects of the invention will be referred to in the specification and pointed out in the claims.

Referring to the accompanying drawings, which illustrate the several features of the kiln, Figure 1 is a longitudinal, vertical section through a portion of a complete kiln. Fig. 2 is a similar view showing a modified construction. Fig. 3 is a section on the line 3-3 of Fig. 2. Fig. 4 is a section on the line 4-4 of Fig. 3. Fig. 5 is a section on the line 5-5 of Fig. 1. Fig. 6 is a section on the line 6-6 of Fig. 1. Fig. 7 is a section on the line 7-7 of Fig. 1. Fig. 8 is a section on the line 8-8 of Fig. 1. Fig. 9 is a section on the line 9-9 of Fig. 1. Figs. 10 and 11 are plan views of kilns showing various water-smoking flue arrangements, and Figs. 12 and 13 are detail views of a modified construction of the connection between the lateral and main draft flues.

It is to be understood that the present invention may be applied to any of the well-known forms of compartment kilns, either single or double battery or *en bloc*, etc. As is well known, kilns of this type are provided with a plurality of communicating compartments which are adapted to receive the ware to be burned. The various compartments

are progressively fired. The waste heat from the compartment being fired being conducted to the compartments containing the green ware in front and receiving air to support combustion from the previously fired and cooling compartments in the rear. The green ware is placed in the kiln in a compartment somewhat in advance of the compartment being fired, and the burnt ware is removed from a compartment somewhat in the rear and after the ware has cooled. In the present instance the kiln consists of a plurality of compartments A, B, C and D. These compartments are separated by walls 1 and are provided

with end walls 2, an arched top 3, and partially perforated floors 4. The end walls 2 are provided with doors 5 which permit access to be had with the interior of the kiln. Arranged along each side of each compartment and lying parallel to the walls 1 are bag-walls 6 behind which the heat used in burning is generated. The heat rises from behind the bag-walls and, being deflected by the arched top 3, passes down through the ware and through the perforated floor where it is conducted to the next compartment through flues 7 and 8. The flues 7 and 8, in addition to transmitting the heated air from the burnt compartment to the unburnt compartments ahead thereof, also conduct the air to support the combustion of the fuel from the burnt compartments in the rear thereof. The exit out of the compartments and the entrance into the flues is through the perforated floors, while the entrance into the compartments from the flues is through the bag-walls and through ports 9 at the bottom of the bag-walls and at the ends of the flues. The ports 9 are located adjacent to and below burner openings 10 placed within the division walls 1 and discharging behind the bag-walls. As the air, which is in a heated condition, is the lighter and is introduced into the compartments below the gas, a better mixture is obtained which results in more complete combustion. To permit the burners 10 to be individually supplied with air the flues 7 and 8 are constructed as follows:

The flues 7 and 8 lie beneath the perforated floors 4 and are separated by division walls 11 having expansion joints 24. At the extreme left end of the kiln, as seen in Figs. 1 and 2, the flues 7 and 8 communicate with

a lateral flue 12 which is connected to a similar flue at the other end of the kiln by a tunnel 27 which is a well-known part of kilns of this type. The lateral flues 12 and 5 the tunnel 27 permit the end compartments of the kiln to communicate with each other. The flues 7 are of a length substantially the same as the width of the compartments and said flues 7 supply air to the left bag-walls 10 of the compartments. The flues 8 are of a length approximately double the width of the compartment and supply air to the right bag-walls of the compartments as seen from Fig. 1. The flues 8 pass under two compartments 15 and the floors of the compartments above the right end of the flues 8 are solid as will be seen from Fig. 1. The flues 7 which are the shorter, are arranged in a longitudinal line, while the longer flues 8 20 are arranged in a staggered form. This arrangement permits the gas burners to be individually supplied with air. The flues 7 and 8 connect with lateral draft tunnels 13 which in turn connect with a main draft tunnel 25. The main draft tunnel 25 connects with a draft appliance such as a fan or stack (not shown) in any well-known manner. In Fig. 6 the lateral draft flues 13 connect directly with the main draft flue 25, 25 while in Figs. 12 and 13 a modified construction is shown. In this construction the flues 13 and 25 are provided with up-takes 28 and 29 which extend to the surface of the ground where they are connected by a 30 removable hood 30. When the hood 30 is not in use, the up-takes may be closed by caps. The heated air from the burning compartment is conducted into one of the flues 13 after it has spent its heat in heating the 35 ware in the advance compartments. The burners 10 may be supplied with gas through down-takes 14, shown in Fig. 2, and which pass through the division walls 1. The down-takes 14 extend from lateral gas tunnels 15 in the upper portion of the kiln. The communication between the tunnels 15 and the down-takes 14 are controlled by valves 16. The tunnels 15 receive gas from a main gas duct 17 through ducts 18. In 40 Figs. 1 and 5 to 9 inclusive a different construction of gas flues is shown. In this construction the gas ducts lie beneath the kiln. As shown in the beforementioned views, the burners 10 are connected to up-takes 19 which lie within the division walls 1. At their lower ends the up-takes 19 connect with lateral horizontal ducts 20 which lie beneath the flues 7 and 8. The ducts 20 communicate with the main gas ducts 21 45 lying along the sides of the kiln below the ground line, as will be seen from Fig. 9. The communication between the main gas duct 21 and the ducts 20 is controlled by valves 22. In this construction the up-takes 19 for the burners 10 of the left bag-

walls of the compartment occupy the extreme right end of the flues 8, while a dead space 23 is provided between some of the walls 11 for the up-takes 19 of the burners 10 of the left bag-walls of the compartments. To permit the up-takes 19 of the left bag-walls of the compartments to communicate with their gas burners 10, a short horizontal duct 26 is provided in the division walls 1. As will be seen from Fig. 7, the 70 dead spaces 23 alternate with each set of flues 7 and 8, there being two long and two short flues to each set.

To permit the green ware to be water-smoked the kiln may be provided with any 80 well known type of water-smoking flue or the following: In Figs. 3 and 10, the kiln is provided with water-smoking flues 31 which extend along the sides of the kiln and are connected to the compartments by hoods or 85 removable ducts 32 through ports 33 in the top of the compartments. When the kiln is constructed in a double battery form, the opposite ends of the water-smoking flues are connected by lateral ducts (not shown) but 90 which are well known in the art. In Fig. 11, which shows a double line of compartments constructed *en bloc*, a water-smoking flue 34 is placed centrally between the compartments and is connected with the compartments by ducts 35 and ports 33 similar to the construction shown in Fig. 10.

The mode of operation is as follows, (see Figs. 1 and 2): Assuming that the compartment C is being fired, the air to support 100 combustion enters the compartment C on one side from compartment B through its perforated floor through the long flues 8 and behind the right bag wall 6. On the other side the air enters behind the left bag wall 105 and is conducted from compartment B through the shorter flues 7. In practice a plurality of compartments to the left of compartment C are used in pre-heating the air and the heated air from compartment A 110 enters compartment B in the same manner as the air from B enters C. The air originally enters the kiln through the doors 5, the wickets of the first pre-heating compartment being broken open. The direction of 115 firing is shown by the arrow, and the ware in a plurality of compartments to the right of the compartment being fired is pre-heated by the products of combustion from the burning compartment. The products of 120 combustion from the burning compartment and from one pre-heating compartment to another are conducted in the same manner and through the same ports and flues as is the air used to support combustion in the 125 burning compartment.

Having described my invention, I claim:

1. A kiln provided with a plurality of compartments, bag-walls at each side of said compartments, perforated floors for said 130

compartments, said kiln being provided with burner openings behind said bag-walls, and individual air-flues for said burner openings which lie beneath and communicate with said perforated floors.

2. A kiln provided with a plurality of compartments, bag-walls at each side of said compartments, perforated floors for said compartments, said kiln being provided with 10 burner openings which discharge behind said bag-walls, and individual air-flues for said burner openings lying beneath and communicating with said perforated floors, the flues for the burner openings on one side of 15 the compartment being of greater length than the flues for the burner openings on the other side of the compartments.

3. A kiln provided with a plurality of compartments, bag-walls at each side of said 20 compartments, perforated floors for said compartments, said kiln being provided with burner openings which discharge behind said bag-walls, and individual air-flues for said burner openings lying beneath and communicating with said perforated floors, the 25 flues for the burner openings on one side of the compartments being of a length approximately equal to the width of the compartments, while the flues for the burner openings on the opposite side being approximately 30 twice the length of the first named flues.

4. A kiln provided with a plurality of compartments, bag-walls at each side of said 35 compartments, perforated floors for said compartments, said kiln being provided with burner openings which discharge behind said bag-walls, and individual air-flues for said burner openings lying beneath and 40 communicating with said perforated floors, the flues for the burner openings on one side of the compartments being arranged in longitudinal lines, while the flues for the burner 45 openings on the other side of the compartments are arranged in a staggered form.

5. A kiln provided with a plurality of compartments, bag-walls at each side of said compartments, perforated floors for said compartments, said kiln being provided with 50 burner openings which discharge behind said bag-walls, and individual air-flues for said burner openings lying beneath and communicating with said perforated floors, the flues for the burner openings on one side of the compartments being arranged in longitudinal lines while the flues for the burner 55 openings on the other sides of the compartments are arranged in a staggered form, the floor above the right ends of the longer flues 60 being solid.

6. A kiln provided with a plurality of compartments, perforated floors for said compartments, bag-walls at each side of said compartments, said kiln being provided 65 with burner openings which discharge be-

hind said bag-walls, and individual air-flues for said burner openings lying beneath and communicating with said perforated floor, and the floor above the right ends of the longer flues being solid.

70

7. A kiln provided with a plurality of compartments, bag-walls at each side of the compartments, said kiln being provided with burner openings which discharge behind said bag-walls, individual air-flues for said 75 burner openings connecting said compartments, and gas ducts connected to said burner openings and passing beneath said air-flues.

8. A kiln provided with a plurality of compartments, bag-walls at each side of the compartments, said kiln being provided with perforated floors and with burner openings, individual air-flues for said burner openings connecting said compartments, and gas 85 ducts connected to said burner openings and passing beneath the floors of the kiln.

9. A kiln provided with a plurality of compartments, bag-walls at each side of the compartments, said kiln being provided with perforated floors and with burner openings, air-flues connecting said compartments, and gas ducts passing beneath the air-flues and provided with up-takes which connect with the burner openings, the up-takes for some of 95 the burner openings occupying the ends of some of the air-flues while the remainder of the up-takes pass between the air-flues.

10. A kiln provided with a plurality of compartments, bag-walls at each side of said 100 compartments, perforated floors for said compartments, said kiln being provided with burner openings which discharge behind said bag-walls, individual air-flues for said burner openings lying beneath and communicating with said perforated floors, the flues for the burner openings on one side of the compartments being of greater length than the flues of the burner openings on the other side of the compartments, and gas 105 ducts passing beneath the air-flues and provided with up-takes which connect with the burner openings, some of said up-takes occupying the ends of the longer air-flues and the other up-takes passing between the air-flues.

11. A kiln provided with division walls which form a plurality of compartments, bag-walls at each side of said compartments, gas ducts in said division walls and communicating with said compartments behind the bag walls, and individual air-flues, one for each gas duct connecting and entering said compartments below the gas ducts.

120

12. A kiln provided with division walls 125 which form a plurality of compartments, bag-walls at each side of said compartments, gas ducts in said division walls and communicating with said compartments behind the bag walls, and individual air-flues, one 130

for each gas duct connecting said compartments and communicating therewith below the gas-ducts.

13. A kiln provided with a plurality of compartments and gas ports, bag-walls at each side of said compartments, individual air-flues for said gas ports connecting said compartments, lateral draft flues connected to said air-flues, a main draft flue, and a 10 removable hood connecting said draft flue.

14. A kiln provided with a plurality of compartments and gas ports, bag-walls at each side of said compartments, individual air-flues for said gas ports connecting said 15 compartments, lateral draft flues connected

to said air-flues, a main draft flue, up-takes extending from said draft flues, and a removable hood connecting said up-takes.

15. A continuous kiln comprising a unitary structure provided with a plurality of compartments both rearwardly and forwardly communicating and having water-smoking openings, bag-walls at each side of said compartments, air flues connecting said compartments, a water-smoking flue 20 for said kiln, and removable ducts connecting said water-smoking flue and said openings.

In testimony whereof I affix my signature,
ROY H. McELROY.
